UNITED STATES PATENT OFFICE.

JAMES BROADHEAD, OF CORNWALL, NEW YORK, ASSIGNOR TO MARY BROADHEAD, OF SAME PLACE.

MACHINERY FOR MANUFACTURING FELTED AND NAPPED FABRICS.

SPECIFICATION forming part of Letters Patent No. 355,130, dated December 28, 1886.

Application filed August 14, 1886. Serial No. 210,890. (No model.) Patented in England March 5, 1885, No. 2,922.

To all whom it may concern:

Be it known that I, JAMES BROADHEAD, of Cornwall, in the county of Orange and State of New York, United States of America, have 5 invented a new and useful Improvement in Machinery for Manufacturing Felted and Napped Fabrics; and the following is declared to be a description of the same.

Letters Patent for this invention were duly 10 granted to me in Great Britain under date of March 5, 1885, No. 2,922.

The object of my invention is to provide an improved machine or apparatus by means of which wool or other fiber, without its being 15 made into yarn, can be incorporated with a fabric made from jute, cotton, or other material so as to form virtually part thereof and give the appearance and in great measure the utility of woolen goods made in the ordinary 20 way.

According to my invention I provide means whereby the fabric to be treated is conveyed by carriers so as to impart the requisite tension thereto in proximity to a series of needles 25 or pinchers, and upon this fabric loose wool or other fiber is placed, it preferably being led in as a continuous layer or bat upon and along with the cloth.

The frame carrying the needles has a reciprocating up-and-down and side-to-side movement imparted to it, so that the needles penetrate a great number of times but at different places through the layer of wool or other fiber and the fabric beneath, the said needles 35 being of such a construction, as hereinafter explained, that they take down at each downward movement some of the woolen or other fibers, so that they are passed partly through the fabric beneath, of which they then form 40 part, the ends of the fibers projecting from each side of the fabric, whereby when the fabric is completed a cloth having the appearance of a good woolen cloth is produced. The head carrying the needles is preferably operated to and fro laterally by a cam with a number of throws, preferably three, so that the said 45 needles penetrate the cloth a great number of times in lines that are not parallel to the

edges and give a very complete incorporation of the wool fibers with the cloth. The needles 50 are made in such a manner that they effectually take down the fibers into the fabric, but on their return movement they do not disengage the fibers so taken down into the fabric. This I effect by making the body of the needle 55 triangular in cross-section, and by cutting out of the angular edges notches, so as to form ledges or barbs, (preferably three at each angle,) and pointing downward toward the point of the needle. These ledges or barbs engage 60 with the fibers and carry them into the fabric as the needles penetrate it; but on the return motion the fibers are not acted upon by the ledges or barbs, they having on their opposite parts inclined surfaces, which allow the 65 needles to free themselves and leave the fabric without pulling out the fibers or injuring the threads of the fabric, owing to there being no projections outside the general longitudinal lines of the needle. 70

In the drawings, Figure 1 is a longitudinal section of an apparatus constructed according to my invention. Fig. 2 is a transverse section of the same, being taken along the line 1 2 in Fig. 1. Fig. 3 is an enlarged view of one of 75 the improved needles used in the machine, and Fig. 4 a face view of the cam for imparting the lateral to and fro motions to the needle-frame.

The fabric A to be treated is wound upon a beam or roller, A', and passes therefrom through 80 a tension device or brake, B, to a pair of rollers, C C', arranged in rear of and in proximity to the needling mechanism, hereinafter more particularly described. The tension device B consists of two rollers, D D', fitted to rotate 85 in a frame, a, mounted on an axle, E, journaled in the frame of the machine, and having fast to one end thereof a worm-wheel, F, gearing with a worm, G, by means of which the worm-wheel F is revolved and the angle of the frame a 90 varied according to the amount of tension required to be put on the fabric A. The worm-wheel G is operated by a hand-wheel, G'.

The bat of fiber K to be incorporated with the fabric A is passed from a roller, H, to the 95 rollers C C' over a creeper or endless band of

battens I, the upper roller, C', being a compressing-roller, pressing the fiber upon the fabric A. The fabric A, in conjunction with the bat of fiber K, passes from between the rollers C C' over a grid-frame, L, where the combined fabric and fiber is operated upon by the needles N, one of which is shown on an enlarged scale in Fig. 3. These needles are carried by a frame, M, to which a reciprocating up-and-down motion is given by means of eccentrics O, fast on the driving-shaft P, causing the said needles to penetrate the fabric A and carry with them the fiber from the bat K.

In addition to the vertical reciprocating motion imparted to the needle-frame by the eccentrics O, the said needle-frame also receives, by means of the three-throw cam Q (shown in plan, Fig. 4) and lever R and link S, a to-and-fro lateral motion, whereby the needles are caused to move in different vertical planes to penetrate the bat and fabric. The cam Q is operated by a worm, z, on the driving-shaft P, in gear with a worm-wheel, y, fast on the cam-shaft x.

25 My improved needle is shown in elevation and cross-section in Fig. 3. It is illustrated as being triangular in cross-section, notches being cut out of the angular edges at intervals along the length of the needle or a portion 30 thereof, so as to form equal ledges or recesses b, which, when the needles descend, engage the fibers K and carry them through the fabric A, but which, as the needles rise, disengage themselves from the fiber, leaving it projecting 35 from the under side of the fabric, the needles freeing themselves and rising out of the fabric without pulling out the bat or wool from the fabric or injuring the fabric. The fibers are incorporated with the fabric by being acted 40 upon by the needles, as described, while the fabric and fibers are drawn along progressively, after which the fabric passes beneath a roller, T, and over a roller, U, thence to the take-up roller or work-beam V, upon which it is wound, 45 the ordinary take-up mechanism being employed to rotate the beam V at the necessary speed required to wind the finished fabric as it passes from the needling mechanism.

The roller U, by means of which the feeding of the fabric through the machine is effected and over which the finished fabric passes, is preferably covered with card-clothing, c, which takes hold of and effects the drawing along of the finished fabric evenly 55 and progressively, and consequently without weakening the fabric. The roller U is operated to draw the fabric from the machine by means of a ratchet-wheel, 1, on a shaft, 2, furnished with tooth-wheel 3, gearing with 60 another wheel, 4, on the axis of the roller U. At each movement of the eccentrics O the pawls 5, carried on arms 6, are operated by the rod 7, and actuate the wheel 1 and move it partly around to move the roller.

65 To insure the uniform and simultaneous

feeding of the fabric A and the bat of fiber K at the same speed as the finished fabric is drawn from the needling mechanism by the roller U, the creeper or endless band of battens I, by which the bat of fiber is conducted to the needling mechanism, is driven by a band, Y, directly from a pulley on the shaft of the roller, on which the cloth on the work-beam V bears, the said shaft-pulley and roller 8 being driven at the same speed as the roller U by gearing from the axis 2, the gearing and driving parts being all so relatively arranged and proportioned that the feeding and withdrawing operations are simultaneously conducted at equal speeds without straining or sagging the material.

The distance to which the needles are caused to penetrate the fabric may be regulated as required by means of adjusting-screws W, operated by the hand-wheels X, whereby the bar M, to which the needles are fixed, is adjusted nearer to or farther from the grid-frame L, through which the needles pass in their descent through the fabric.

n are rods or bars over the bat and fabric to 90 retain them in place.

I am aware of the United States Patent No. 173,704, granted February 15, 1876, to M. D. Whipple, and of the patents therein referred to, and others relating to felting by the action of reciprocating needles. My present improvements on the pre-existing devices allow for feeding in the bat of wool or similar fibrous material with greater uniformity and without the risk of injury to the same, and I 100 am able to adjust the parts of the machine and regulate the action of the felting-needles more perfectly than in machines before constructed.

I claim as my invention—

1. The combination, with the beam V and roller 8, and the mechanism for operating the same and drawing the woven fabric through the machine, of the endless belt Y, the belt of battens I, to feed the bat of fiber, the rollers C C', through which both the bat of fiber and the woven fabric pass, the grid-frame L, rods n, and needles N, and needle-frame, substantially as specified.

2. The combination, with the beam V and roller 8, and the mechanism for operating the same and drawing the woven fabric through the machine, of the tension device having rollers D D', frame a, and worm-wheels F and G, the rollers C C', the roller T, and the roller U, covered with card-clothing c, the grid-frame, and needle-frame, substantially as and for the purposes specified.

3. The combination, in a felting-machine, with the grid-frame L, driving-shaft P, cam O, needle-frame M, and needles N, of the connecting-arms between the cam O and frame M, the worm-wheels z y, shaft x, the cam Q, and lever R, and link S, for imparting to the needle-frame and needles an up-and-

105

down and sidewise movement, substantially as specified.

4. The combination, in a felting-machine, of the grid-frame L and rods n, and mechanism, substantially as specified, for moving the fabric, the frame M, and needles N, each needle being triangular in cross-section and pointed, and having notches in the angular

edges, substantially as and for the purposes set forth.

Signed by me this 14th day of July, A. D. 1886.

JAMES BROADHEAD.
